[57] CLAIM

We claim the design of nylon covered anterior trunk support, as shown and described.

DESCRIPTION

FIG. 1 is a top plan view of a nylon covered anterior trunk support showing our new design;

FIG. 2 is a left side elevation view thereof;

FIG. 3 is a right side elevation view thereof;

FIG. 4 is a front elevation view thereof; and,

FIG. 5 is a perspective view thereof, the chair and straps shown in broken lines are for illustrative purposes only and form no part of the claimed design.
